AIR MOTOR AND PUMP

William B. Weis, Detroit, Mich., assignor, by direct and mesne assignments, of ninety per cent to Leah Helpert and ten per cent to Robert A. Sloman, both of Detroit, Mich.

Application February 27, 1950, Serial No. 146,570

8 Claims. (Cl. 121—164)

1

This invention relates to an air motor and a novel control mechanism therefor, and more particularly to an air operated motor and pump capable of pumping liquids, particularly oil.

It is the object of the present invention to provide an air motor construction together with a novel valve and valve controlling mechanism whereby upon the application of compressed air the motor will be continuously operating and will automatically reciprocate in view of its positive acting control mechanism, and this motor may be used for many different purposes.

It is the object of the present invention to provide such motor and pump for use in draining oil from one enclosure, such as a vehicle crank case, and pumping the same directly into an oil drum or other suitable storage tank.

It is the further object of this invention to provide a device of this type which can be readily placed within the threaded aperture of an oil drum and mounted thereon, employing a suitable oil drain hose attached to said pump at one end, and with its inlet positioned within the receptacle from which it is desired that the fluid or oil be drained.

It is the further object of this invention to provide an air motor and pump together with an automatically operable positive acting control valve mechanism for regulating the direction of compressed air to one side or the other of said motor.

These and other objects will be seen from the following specification and claims in conjunction with the appended drawings in which:

Fig. 1 is a perspective view of the air motor and pump is mounted upon a drum which is fragmentarily shown.

Fig. 2 is side elevational view of said air motor and pump.

Fig. 3 is an enlarged section on line 3—3 of Fig. 2.

Fig. 4 is a section on line 4—4 of Fig. 3.

Fig. 5 is a section on line 5—5 of Fig. 3.

Fig. 6 is a fragmentary section on line 6—6 of Fig. 3.

Fig. 7 is a fragmentary section on line 7—7 of Fig. 3.

Fig. 8 is a fragmentary section on line 8—8 of Fig. 4.

Fig. 9 is a partially sectioned fragmentary view of a slight variation in the construction of the motor and pump housing, and a slight variation in the method of mounting on the drum fragmentarily shown.

Fig. 10 is a section on line 10—10 of Fig. 9.

2 Fig. 11 is a section on line 11—11 of Fig. 10; and

Fig. 12 is an elevational view partially broken away and sectioned illustrating the present air motor without the pump.

It will be understood that the above drawings illustrate merely a preferred embodiment of the present invention, and other embodiments are contemplated within the scope of the claims hereafter set out.

Referring to Fig. 1 an oil drum D is fragmentarily shown having a threaded inlet opening 11 at its upper end into which the present motor and pump are mounted. The air motor is generally indicated at A and the pump attached thereto is indicated at B. The compressed air supply conduit is shown at C, there being a suitable petcock E in said conduit and joined to the motor housing as best illustrated in Fig. 2. The oil drain flexible pipe F has a fitting 20 at one end for connection with the fluid inlet fitting 21 which extends from pump housing B, the opposite end of said pipe being adapted for insertion within the receptacle from which it is desired to pump fluid, such as oil from a vehicle crank case, which is to be pumped directly into the drum D.

The downwardly depending legs 29 which extend from pump housing B, as also illustrated in Figure 7, are threaded at 30 upon their outer surfaces, being adapted for threaded insertion and securing within the threaded opening 11 of said drum.

Referring to Figs. 2 and 3 the motor and pump includes the elongated housing 12 with the central cylindrical chamber 13, said housing having a cylindrical portion 14 which terminates at its upper end in the flange 15.

Cylinder head 16 is aligned with housing 12 and positioned thereover, being firmly secured thereto by the four threaded studs 19 which extend upwardly through said flange and into said cylinder head as shown in Fig. 2.

The air motor includes the elongated housing 17 and the integral cylindrical head 16 at its lower end, said housing having a central cylindrical bore 18 which extends from said head throughout the length of said housing.

Fitting 20 on flexible oil hose or pipe F is joined as shown in Fig. 1 to the inlet fitting 21, which as shown in Fig. 7 is threaded into a corresponding opening in the lower end of pump housing 12, there being an upright passage 25 providing fluid communication from the inlet opening 24 in fitting 21 to the pump chamber 13.

The ball check valve 22 is normally maintained by a suitable spring shown in Fig. 7 against the conical valve seat 23 within inlet fitting 21 whereby fluid such as oil may flow inwardly only, and the action of the pump hereafter described will not deliver any fluid out through fitting 21.

At the lower end of pump chamber 13 is a delivery passage including conically shaped valve seat 26 within which is movably positioned the ball valve 27 normally held against said seat by the coil spring which is shown. This ball check valve is within and supported by the fluid delivery fitting 27' with delivery opening 28.

Piston rod 31 is housed within motor housing 17 and is adapted for reciprocal movement through a central opening formed through the cylinder head 16. Leather cup 32, metallic disk 33, as well as washer 34 are mounted over the extension 35 of reduced diameter at the upper end of shaft 31, and are secured thereon by the nut 36 to form the upper piston within the air motor.

Mounted upon the extension 37 at the opposite end of rod 31 is the leather cup 38; metallic disk 39 and the washer 40, secured thereon by the rivet element 41 shown. It is contemplated that the extension 37 could be threaded as shown in Fig. 9, and with this lower piston assembly secured such as by the nut 83.

The air motor includes the bore 18 as well as the cylindrical chamber 42 between the upper end of piston 38 and cylinder head 16 which is provided upon the downward movement of said piston such as shown in Fig. 5. The compressed air conduit C and the petcock E joined thereto is mounted upon the lower end of housing 17 with the threaded outlet 43 of said petcock positioned within the corresponding threaded opening 44 formed within the cylinder head 16 as shown in Fig. 5. Said opening terminates in the compressed air supply passage 45 which is adapted to supply compressed air alternately to either of the passages 46 or 47, passage 46 supplying compressed air to chamber 42 and passage 47 being adapted to supply compressed air to bore 18.

Compressed air delivered through passage 46 operates upon the lower piston 38 for effecting downward movements thereof within the chamber 13 of the pump 12, and this downward movement is adapted to pump through the action of said piston fluid or oil from the interior of chamber 13 through the fluid outlet fitting 27' and directly into the fluid drum, said fitting being centrally positioned with respect to the opening 11 in the top of said drum.

There is also an exhaust passage formed within the cylinder head 16 which is adapted for alternate communication with either of the chamber exhaust passages 48 and 49, depending upon the positioning of the rockable valve element 51 shown in Figure 5. When compressed air is supplied from passage 45, through valve groove 52 and through passage 46 into chamber 42 to effect downward movement of piston 38, then exhaust from bore 18 under the downward action of piston 32 is forced through the passage 49, valve groove 53 and out through the exhaust passage 50. With the valve 51 rotated to the dotted line position 51' shown in Figure 5 the flow is reversed with compressed air being supplied through groove 52 and passage 47 up into bore 18, and with exhaust from chamber 42 under the upper action of piston 38 projected through passage 48, valve groove 53 and exhaust passage 50.

Figure 4 illustrates the construction of the valve 51 and its positioning within the cylinder head 16. The valve 51 with the grooves 52 and 53 upon opposite sides thereof, is generally conical in shape, and is adapted for positioning adjacent the conical seat 54, with the valve stem 55 projecting from valve 51 and transversely thru cylinder head 16.

The thrust screw 56 is threaded into cylinder head 16 for cooperative retaining engagement against the outer end of valve 51 normally maintaining the same in relation to its seat 54, there being provided a suitable lock nut 57 for securing said thrust screw in the desired adjusted position relative to said valve.

The opposite reduced threaded end 58 on valve stem 55 extends beyond cylinder head 16 and has secured thereto the crank 59 by means of the nut 60 and the lock nut 61. A central circular opening 62 is formed within crank 59 as shown in Figure 2, being adapted to cooperatively receive the transverse stop pin 63 which is secured within a lateral opening in said cylinder head and which projects into the circular opening 62 of said crank to limit its pivotal movements.

Transverse pin 64 is riveted or otherwise suitably secured to the outer end of crank 59, and a corresponding pin 65 projects outwardly from the rockable disc 66 in substantial parallel relation, there being a suitable coil spring 66' interposed between and interconnecting the two pins 64 and 65.

The rockable disc 66 is generally semi-circular in form, including the movement limiting or stop surfaces 67 and 68 which are also adapted for intermittent cooperative registry with the stop pin 63 as shown in Figures 2 and 1. The control disc 66 is centrally secured upon the outer end of the rockable pinion 70 as by the rivet construction 71 shown in Figure 4 to assure movement in unison of said disc and pinion. As shown in Figure 8 the outer end of the valve stem 55 has concave recesses 55' adapted to be retainingly received within correspondingly shaped portions of the crank 59 to assure movement in unison between said crank and valve stem.

Rotatable pinion 70 is loosely housed within the transverse circular opening 69 in cylinder head 16 and is in mesh at all times with the gear teeth which form a part of the rack gear 73 on one side of the vertically reciprocal shaft 72, as shown in Figures 3, 4 and 6.

Thus it is apparent that vertical movements of the shaft 72 will affect rotary movements of the pinion 70 in one direction or the other, this in turn effecting a rocking movement in one direction of the other of the control disc 66, joined to the crank 59 by the coil spring 66'. As will be apparent from Figure 2 initial rocking movement in one direction of the disc 66 from the position shown in Figure 2 in engagement with the pin 63, will have no effect upon the position of the crank 59 until the pin 65 on said disc passes dead center relation with respect to pin 64 and the pivotal mounting point 58 of crank 59.

After the pin 65 passes said dead center the spring 66' will be effective to move the crank 59 from a position shown in Figure 2 upwardly in a clockwise direction until the boundary of the circular opening 62 re-engages the pin 63 upon its opposite side.

The pin 63 is also adapted to limit the rocking movement of disc 66, and this motion will be limited when the surface 67 is in engagement with pin 63. Thus there is provided a novel

mechanism for obtaining a quick and positive action of the crank 59 and the valve to which it is connected. On a movement of the rack supporting shaft 72 in the opposite direction it is apparent that the pinion, loosely mounted around valve stem 55, will rock in the opposite direction causing a change in the direction of movement of the disc 66. There again the disc will not be effective to change the position of the crank 59 until the pin 65 on said disc passes beyond dead center; or in other words passes beyond a line extending between the pin 64 and the mounting point 58 of said crank.

Referring to Figure 3 it will be seen that the rack operating shaft 72 is in its uppermost position, said shaft being slidably positioned through a corresponding opening in the cylinder head substantially parallel with piston rod 31. Shaft 72 merely floats within the opening in cylinder head 16 and is moved upwardly by the upward movement of the piston assembly 38 to the position shown in Figure 3, being the uppermost position of said shaft and the rack carried thereby.

Upon downward movement of the piston assembly 38, it will be seen that the shaft 72 will remain stationary until the piston has travelled almost its complete path of movement. As it reaches the lower end of chamber 18 said piston assembly bears downwardly upon the rack operating shaft 72 moving the same downwardly corresponding to the lowermost position of the piston assembly 38, and with the lower end of shaft 72 projected below cylinder head 16 to the extent equal to the amount it projects above said cylinder head in Figure 3.

The upper end of the rod 72 at 74 is adapted for engagement with piston assembly 32, whereas the lower end 75 of said shaft is adapted for intermittent cooperative registry with piston assembly 38.

Due to the lost motion between either piston assembly and the corresponding end of the rack operating shaft 72 it is apparent that a greater portion of the motion of said pistons will have no effect upon the shaft 72. Furthermore, the initial downward or upward movement of said shaft under the action of either of the piston assemblies, while it initiates a rocking movement of the control disc 66, will still be ineffective to operate or change the positioning of the control valve 51 which determines to which cylinder or chamber compressed air is to be supplied. It is only after the disc 66 and the pin 65 carried thereby has rocked slightly past the dead center position above described that there will be any action of the crank 59, and this action will be a quick snap action providing for a positive change in the position of the valve 51 from one control position to the other.

In other words under the action of the spring 66 the crank 59 is adapted for a quick snap action from one position of control to the opposite position of control, with both movements being limited by the projection of the pin 63 into the enlarged circular opening 62 of said crank. With the crank keyed to the valve stem 55 in the manner shown in Figure 8 it also follows that the valve 51 will be positive acting and will change quickly from one position of control to the other.

Therefore, this valve is effective to control the flow intermittently from chamber 18 to chamber 42, and control the exhaust flow from chamber 42 or from chamber 18. In other words compressed air will be supplied to chamber 42 until the piston assembly 38 has practically completed its downward stroke, after which said valve will

be quickly changed over so that the compressed air source is delivered to chamber 18 on the under side of piston assembly 32. Therefore it is possible to effect a continuous reciprocal movement of the two pistons within their respective chambers 18 and 42.

During the upward movement of piston assembly 38 oil will be drawn into the pump chamber 13 from the conduit F, ball valve 27 being spring closed. And upon the downward movement of piston assembly 38 the fluid within chamber 13 will be pumped out through the fitting 27', through the opening 28 therein, dropping down into the interior of drum D in the manner shown in Figure 1, ball valve 22 being closed. In other words chamber 13 may be regarded as a pumping chamber whereas the two chambers 18 and 42 may be regarded as the operating chambers. Compressed air is supplied intermittently to the chambers 18 and 42 to thereby produce the pumping action of the piston assembly 38.

Referring to Figure 9 of the drawings, there has been a slight change in the present embodiment of the invention, wherein the block 76 is threaded at its lower end at 77 and projected down into the threaded opening 11 in the top of the drum D.

Block 76 is bored to receive the inlet fitting 21, which is of the same construction as that shown in Figure 7, and which includes the ball check one way inlet valve 22. Furthermore, the block 76 is also bored to receive the outlet fitting 27' which is of the same construction as that shown in Figure 7 and which also includes the one way ball check valve 27. Fluid drawn in through the fitting 21 enters the pumping chamber 13 through a similar passage 25, and upon downward movement of the piston assembly 38 said fluid is pushed outwardly through the downwardly extending passage 28 and thence through the outlet fitting 27'.

Instead of the solid enclosed housing 12-14 shown in Figure 3 there is provided a hollow cylindrical wall 79 preferably constructed of a transparent plastic substance, still defining the pumping chamber 13 therein, the respective opposite ends of said cylindrical wall 79 being cooperatively joined to the block 76 and to the lower end of the cylinder head 16 which forms a part of the housing 17.

As shown in Figures 10 and 11 a plurality of tie rods 80 are employed which project upwardly through slots 81 in said block, being anchored therein, and with the upper ends of said tie rods threadably joined at 82 to the lower end of the cylindrical housing 17. By this construction the transparent tubular element 79 is effectively secured with respect to the block 76 and the upper housing 17.

Another slight variation or adaptation of the present invention is shown in Figure 12 wherein there is preferably a unitary cylindrical housing 84, open at its opposite ends, and including a central cylinder head such as shown in the drawings at 16. The upright reciprocal piston rod 85 extends through the cylinder head, and upon one end of said rod is mounted a piston assembly 86, and upon its other end a piston assembly 87. The same control mechanism above described with respect to Figures 3 and 4 is employed within the cylindrical housing 84 for effecting reciprocal movements of the piston assemblies 86 and 87 therein.

However, instead of acting as a pump there are provided upon opposite ends of the respective

piston assemblies the rods 88 and 91. Rod 88 with a suitable connector or transverse opening 89 at its outer end, is joined to the piston assembly 86 as by the nut 90. On the other hand the rod 91 with transverse opening 92 at its outer end is joined to the reciprocal piston assembly 87 as by the nut 93.

Thus there is shown in Figure 12 an air motor which is operated in the identical fashion as the air motor described with respect to Figures 1 through 11, with the exception that the pumping device has been eliminated. In other words, reciprocal movement of the pistons is adapted to effect reciprocal movement of the two extension rods 88 and 91, which movements may be utilized for various purposes.

Having described my invention reference should now be had to the claims which follow for determining the scope thereof.

I claim:

1. A fluid motor comprising a hollow elongated housing having a central cylinder head defining chambers upon opposite sides thereof, a reciprocal rod extending through said head and carrying pistons upon opposite ends thereof within said housing, a pressure fluid source joined to said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, a pivoted crank joined to said valve stem on the exterior of said housing for intermittently rocking said valve, a longitudinally reciprocal shaft spaced from said rod and extending through said head and outwardly therefrom with its opposite ends adapted for alternate engagement and movement with said pistons, a rack gear on said shaft, a pinion in mesh therewith and loosely journaled within said head and projecting from said housing, a rockable control disc on the exterior of said housing secured to said pinion, and resilient control means interconnecting said disc and the free end of said crank for effecting automatic intermittent control movements of said valve.

2. A fluid motor comprising a hollow elongated housing having a central cylinder head defining chambers upon opposite sides thereof, a reciprocal rod extending through said head and carrying pistons upon opposite ends thereof within said housing, a pressure fluid source joined to said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, a pivoted crank joined to said valve stem on the exterior of said housing for intermittently rocking said valve, a longitudinally reciprocal shaft spaced from said rod and extending through said head and outwardly therefrom with its opposite ends adapted for alternate engagement and movement with said pistons, a rack gear on said shaft, a pinion in mesh therewith and loosely journaled within said head and projecting from said housing, and

control means on the exterior of said housing interconnecting said pinion and the free end of said crank to effect automatic intermittent control movements of said valve.

3. A fluid motor comprising a hollow elongated housing having a central cylinder head defining chambers upon opposite sides thereof, a reciprocal rod extending through said head and carrying pistons upon opposite ends thereof within said housing, a pressure fluid source joined to said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, a pivoted crank joined to said valve stem on the exterior of said housing for intermittently rocking said valve, a longitudinally reciprocal shaft spaced from said rod and extending through said head and outwardly therefrom with its opposite ends adapted for alternate engagement and movement with said pistons, a rack gear on said shaft, a pinion in mesh therewith and loosely journaled within said head and projecting from said housing, a rockable control disc on the exterior of said housing secured to said pinion, and resilient control means interconnecting said disc and the free end of said crank for effecting automatic intermittent control movements of said valve.

4. A fluid motor comprising a hollow elongated housing having a central cylinder head defining chambers upon opposite sides thereof, a reciprocal rod extending through said head and carrying pistons upon opposite ends thereof within said housing, a pressure fluid source joined to said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, a pivoted crank joined to said valve stem on the exterior of said housing for intermittently rocking said valve, a longitudinally reciprocal shaft spaced from said rod and extending through said head and outwardly therefrom with its opposite ends adapted for alternate engagement and movement with said pistons, a rack gear on said shaft, a pinion in mesh therewith and loosely journaled within said head and projecting from said housing, a rockable control disc on the exterior of said housing secured to said pinion, and a coiled spring with one end joined to the free end of said crank and with its other end joined to said disc for effecting automatic intermittent positive control movements of said valve.

5. A fluid motor comprising a hollow elongated housing having a central cylinder head defining chambers upon opposite sides thereof, a reciprocal rod extending through said head and carrying pistons upon opposite ends thereof within said housing, a pressure fluid source joined to

said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, a pivoted crank joined to said valve stem on the exterior of said housing for intermittently rocking said valve, a longitudinally reciprocal shaft spaced from said rod and extending through said head and outwardly therefrom with its opposite ends adapted for alternate engagement and movement with said pistons, a rack gear on said shaft, a pinion in mesh therewith and loosely journaled within said head and projecting from said housing, a rockable control disc on the exterior of said housing secured to said pinion, and a coiled spring with one end joined to the free end of said crank and with its other end joined to said disc for effecting automatic intermittent positive control movements of said valve, the connections of said spring with said crank and disc with respect to a common center being such that said disc will move said valve from one control position to another only after the disc connection with said spring passes dead center with respect to said common center and the crank connection with said spring.

6. A fluid motor comprising a hollow elongated housing having a central cylinder head defining chambers upon opposite sides thereof, a reciprocal rod extending through said head and carrying pistons upon opposite ends thereof within said housing, a pressure fluid source joined to said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, a pivoted crank joined to said valve stem on the exterior of said housing for intermittently rocking said valve, a longitudinally reciprocal shaft spaced from said rod and extending through said head and outwardly therefrom with its opposite ends adapted for alternate engagement and movement with said pistons, a rack gear on said shaft, a pinion in mesh therewith and loosely journaled within said head and projecting from said housing, a rockable control disc on the exterior of said housing secured to said pinion, resilient control means interconnecting said disc and the free end of said crank for effecting automatic intermittent control movements of said valve, and a stop pin projecting from said housing cooperable with said crank and disc to limit their pivotal movements.

7. A fluid motor comprising a hollow elongated housing having a central cylinder head defining chambers upon opposite sides thereof, a reciprocal rod extending through said head and carrying pistons upon opposite ends thereof within said housing, a pressure fluid source joined to said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, said valve being cone shaped, and a thrust screw adjustably extending into said head and having an arcuate inner portion retainingly engaging said valve.

8. A fluid motor comprising a hollow elongated housing having a central cylinder head defining chambers upon opposite sides thereof, a reciprocal rod extending through said head and carrying pistons upon opposite ends thereof within said housing, a pressure fluid source joined to said head, said head having passages therein for receiving and exhausting pressure fluid and for delivering and exhausting pressure fluid to and from each of said chambers respectively, a rockable valve having an elongated stem journaled within said head and projecting from said housing, said valve being grooved for controlling through said passages respectively the flow of pressure fluid to one chamber and exhaust from the other chamber, and adapted upon movement to reverse said pressure fluid and exhaust from one chamber to the other, a pinion rotatably journaled on said stem, a reciprocal rack gear extending through said head and outwardly therefrom with its opposite ends adapted for alternate engagement and movement with said pistons, and spring means interconnecting said pinion and said valve for effecting intermittent control movements of said valve.
